UNITED STATES PATENT OFFICE.

DAVID B. BUDIN, OF BROOKLYN, NEW YORK, ASSIGNOR OF ONE-HALF TO SAMUEL BAUMOHL, OF NEW YORK, N. Y.

RAILED BARRIER.

1,280,614.

Specification of Letters Patent.

Patented Oct. 1, 1918.

Application filed November 6, 1917. Serial No. 200,555.

To all whom it may concern:

Be it known that I, DAVID B. BUDIN, a citizen of the United States, and a resident of the city of New York, borough of Brooklyn, in the county of Kings and State of New York, have invented a new and Improved Railed Barrier, of which the following is a full, clear, and exact description.

10 Among the principal objects which the present invention has in view are: to prevent the accidental dislodgment of a barrier of the character mentioned; to provide means for installing a barrier of the character mentioned; to lap the marginal casings or to fit between the same; and to simplify the construction and assembly of the parts forming the barrier.

Drawings.

20 Figure 1 is a face view of a barrier constructed and arranged in accordance with the present invention;

25 Fig. 2 is a cross section on an enlarged scale of one of the expanding rails, the section being taken as on the line 2—2 in Fig. 1;

30 Fig. 3 is a cross section on an enlarged scale showing a fragment of a window casing and a top view of a portion of the barrier, the section being taken as on the line 3—3 in Fig. 1;

35 Fig. 4 is a detail view showing in perspective the upper corner of the barrier and the means for securing the same in service;

40 Fig. 5 is a detail view on an enlarged scale and in section, showing one of the lower hanging plates and adjacent frame, the section being taken as on the line 5—5 in Fig. 1;

45 Fig. 6 is a detail view on an enlarged scale partly in section, showing a modified application of the barrier and the handling devices therefor.

Description.

As seen in the drawings, barriers when constructed and arranged in accordance with the present invention, have a series of rails 11. One end of each of the rails is fixedly attached to an upright stile 12. The free ends of the rails 11 are provided with metal loops 13 and 14. The loops 14 are preferably attached to one of the rails 11 at the upper and lower edges of the barrier. Each of the

loops 14 is tapped to provide screw threads for engaging threads on thumb screws 15, the ends whereof bear on the companion rail to bind the lapped rails together for determining the width of the spread of said 60 rails.

From the foregoing, it is obvious that the loops 13 and 14 being permanently attached to one of the rails 11 and normally sliding on the other, the rails are maintained in 65 alignment during the expanding or contracting of the barrier or while the stiles 12 are being separated or drawn together.

70 Barriers of the character shown in the accompanying drawings and herein described are intended for use in connection with window openings, entrances to stairways, and door openings, where it is sought to prevent any person from falling out of or passing through the openings. One of 75 the chief purposes for which the invention is intended, is to prevent the accidental falling from a window when a person is spreading or collecting laundry. When employing the barrier in this connection, the window frame and particularly the stop bead 16 thereof, has on the side thereof, a screw 17 or other suitable hanging device. The screw 17 is withheld from being driven fully home, so that the head of the screw may extend through the enlarged opening 18 of eyelets formed in the angle plates 19 with which the stiles 12 are furnished. The angle plates 19 are made of metal and are permanently secured on said stiles. The upper 80 plates 19, as shown best in Fig. 4 of the drawings, may be extended above the upper end of said stiles. The lower plates are preferably disposed intermediate the ends of the stiles and adjacent the lower ends 85 thereof. The stiles 12 are cut away to form recesses 20, which recesses are covered or partly covered by the plates 19, as seen best in Figs. 5 and 6 of the drawings. The recesses 20 afford space for the heads of the 90 screws 17 when the stiles and plates 19 thereon are adjusted to the said screws.

95 Each of the eyelets has above and opening from the hole 18, a slit 21. The slit 21 is sufficiently wide to receive the shank of 105 the screw 17 and sufficiently narrow to permit the passage therethrough of the head of said screw.

100 As shown best in Figs. 4 and 5 of the drawings, each flange of the plates 19 is 110

provided with an eyelet of the character mentioned. As one of the flanges rests in a plane parallel with the plane of the carrier, the outlet in said flange may engage 5 hanging devices disposed in the face of the opening frames. In this manner, provision is made for installing the barrier in service on windows or other openings where the molding or shape of the opening is not 10 conducive to the employment of the barrier.

The plates 22 are slidably mounted on the ends of the stiles 12. Each plate is provided with a longitudinal slot 23, through 15 which the shank of a screw 24 extends. The screws 24 guide the plates 22 in their movements while wing nuts 25 are employed for clamping or locking said plates in any adjusted position thereof. In service, the plate 20 22 passes under the heads of the screws 17, to prevent the lifting of the barrier. When lifted, the heads of the screws 17 may pass through the enlarged openings 18 of the eyelets in the plates 19, and release the barrier which may then become dislodged from 25 its service location. The advantage of this construction will be recognized when attention is drawn to the fact that these barriers are employed for preventing children 30 leaning out of or falling from window openings, or from doors or other entrance openings to stairways, shafts, or similar locations.

As shown in Fig. 4 of the drawings, the 35 plates 22 may be constructed from angle metal, the flanges 26 whereof extend across the face of the stiles 12 for convenient manipulation by the person adjusting the barrier to the standing structure with which it 40 is associated. It will also be observed that when the plate 22 is moved forward, it covers the recess or opening 20, and passes under the head of the screw 17, whether the same be arranged as shown in Fig. 3 or as 45 shown in Fig. 6.

Claims.

1. A barrier as characterized, and hanging members therefor embodying a plurality of vertically disposed angle plates, the 50 perpendicular flanges whereof being provided with inverted eyelets; a plurality of sliding plates adapted for engaging said angle plates intermediate the ends of said eyelets; and means for locking said sliding

plates in service position for preventing the retraction thereof from engagement with said angle plates.

2. A device as characterized comprising a plurality of telescopically connected members; a plurality of vertically disposed angle plates fixedly mounted on said members at the opposite extremes thereof, said angle plates having each an eyelet for engaging a fixed hanger member; a movable locking plate mounted on the first mentioned members for engaging said hanger member when disposed as in service; and means for locking said plate in the locked position thereof with said hanger member. 70

3. A barrier as characterized having vertical side stiles; a plurality of suspension members for said barrier, said members embodying angle plates, each having inverted eyelets in the opposite flanges thereof, said angle plates being disposed on the exposed corner of each of said stiles to engage suspension members placed in a standing structure in a plane parallel with the plane of said barrier or in planes perpendicular to the plane of said barrier, two of said plates being extended beyond the ends of the stiles to which they are attached so that the ends of the eyelets therein extend above the ends of said stiles for engaging said angle plates 80 below the ends of the eyelets therein; and means for securing said locking plates in operative service relation. 85

4. In a barrier as characterized, means 90 for hanging said barrier, said means embodying a plurality of angle plates permanently mounted on said barrier at the exposed corners thereof, said angle plates having inverted eyelets formed therein and supporting members having screw-like 95 heads adapted for extension through an enlarged portion of each of said eyelets, said heads being adapted to overhang the edges of the contracted portions of said eyelets; and a plurality of locking angle plates slidably mounted on said barrier at the exposed 100 corners thereof adjacent the first-mentioned angle plates, to slide in guided relation to said barrier in lines perpendicular to the flanges of the first-mentioned angle plates; and a plurality of screw members for clamping 105 said locking plates in service relation and in engagement with said hanging plates and said supporting members.

DAVID B. BUDIN.
